Attorney

UNITED STATES PATENT OFFICE.

JOSEPH GRAZIANO, OF NEWBURGH, NEW YORK.

TEMPERATURE-REGULATOR.

1,352,364.

Specification of Letters Patent. Patented Sept. 7, 1920.

Application filed October 15, 1918. Serial No. 262,184.

To all whom it may concern:

Be it known that I, JOSEPH GRAZIANO, a subject of the King of Italy, residing at Newburgh, in the county of Orange and State of New York, have invented new and useful Improvements in Temperature-Regulators, of which the following is a specification.

This invention relates to temperature regulators and is especially designed for use in conjunction with the compressed air supply tanks or reservoirs of compressed air engines.

The object of the present invention is to provide simple and efficient means for automatically regulating the temperature of the compressed air in a compressed air reservoir, maintaining said air at a predetermined temperature best suited for the efficient operation of the engine supplied thereby, said means including an electric resistance element, a rheostat in circuit with said element, and a pressure controlled element in open communication with the interior of said reservoir, which pressure controlled element automatically controls the rheostat for the purpose of throwing in more or less resistance.

With the above and other objects in view, the invention consists in the construction, combination and arrangement of devices hereinafter described and claimed.

The accompanying drawing represents—

A sectional view of the temperature regulating apparatus as applied to a compressed air reservoir.

Referring to the drawings, 1 designates a compressed air tank or reservoir, which, for the sake of convenience, is illustrated as of hollow cylindrical formation, said reservoir embodying oppositely arranged heads 2 and having a compressed air inlet connection 3 through which compressed air is forced from a suitable air compressor into the reservoir. The reservoir is also equipped with an air pressure gage 3' located at a suitable point thereon and in communication therewith.

In carrying out the present invention, I provide within the reservoir 1 an electric resistance element shown in the form of a plurality of resistance coils 4 each of which is disposed around an insulated support 5 shown in the form of a rod extending longi-

tudinally of and within the reservoir 1 and 55 having the opposite ends thereof supported by insulating sockets 6 which are flanged and secured to the heads 2 of said reservoir as shown.

Connected with the reservoir 1 and in 60 open connection therewith, is a pressure-controlled element 7 comprising a chamber which communicates at all times with the interior of the reservoir, by means of a tubular connection 8. The device 7 comprises a 65 diaphragm 9 having an outwardly projecting stem 10 which projects beyond the casing of the device 7 as shown in the drawings and is connected to the short arm 11 of a bell crank lever 12, said lever being pivotally 70 mounted at 13 upon a supporting bracket 14 secured to the outside of the reservoir 1. The longer arm 12 of said bell crank lever is extended to form the operating arm of a rheostat 15, the rheostat 15 being in electrical 75 connection with the resistance element 4 by means of wires 16 and 17, as shown in the drawings.

The connection between the short arm 11 of the rheostat lever and the stem 10 is rendered adjustable by threading the stem 10 and placing nuts 18 upon said stem at opposite sides of said short arm 11 of the bell crank lever. By adjusting the nuts 18, the mean pressure of the air in the reservoir 80 85 may be regulated to obtain the highest efficiency in the use of such compressed air for the operation of the engine. 19 represents the air intake manifold of an air engine, said manifold having the branch supply pipes 20 90 which communicate with the cylinders of the engine (not shown). A conduit 21 connects the reservoir 1 with the manifold 19 and is controlled by regulating the cutoff valve 22 enabling the volume of air delivered from the reservoir 1 to the air engine 95 to be regulated.

From the foregoing description taken in connection with the accompanying drawings, it will now be understood that as the 100 temperature rises and the pressure of the compressed air in the reservoir 1 increases, the lever 12 will be shifted so as to throw in more resistance and conversely, as the temperature and consequently the pressure 105 lowers in the reservoir 1, less resistance will be thrown in to the electrical circuit controlling the resistance coils 4. In this way

the temperature and therefore the pressure of the compressed air in the reservoir is maintained at a predetermined degree.

Having thus described my invention, I claim:

- 5 1. The combination with a compressed air reservoir, of means for automatically regulating the pressure of the air therein, said means embodying an electric resistance element in said reservoir, a rheostat in circuit with said element, and a pressure-operated controller for said rheostat in open communication with said reservoir and directly influenced by the pressure of the air therein.
- 10 15 2. The combination with a compressed air reservoir, of means for automatically regulating the pressure of the air therein, said means embodying an electric resistance element in said reservoir, a rheostat in circuit with said element, a pressure-operated controller for said rheostat in open communication with said reservoir and directly influenced by the pressure of the air therein, said 20 resistance element comprising a plurality of resistance coils in the reservoir, insulated supporting rods for said coils, and insulated sockets for the ends of said rods attached to opposite walls of the reservoir.

25 30 35 40 45 50 55 60 65 70 75 80 85 90 95 99
enced by the pressure of the air therein, and means for adjusting the working connections between the rheostat and said controller to regulate the mean pressure of the air in said reservoir.

3. The combination with a compressed air reservoir, of means for automatically regulating the pressure of the air therein, said means embodying an electric resistance element in said reservoir, a rheostat in circuit with said element, a pressure-operated controller for said rheostat in open communication with said reservoir and directly influenced by the pressure of the air therein, said resistance element comprising a plurality of resistance coils in the reservoir, insulated supporting rods for said coils, and insulated sockets for the ends of said rods attached to opposite walls of the reservoir.

In testimony whereof I affix my signature.

JOSEPH GRAZIANO SON OF ROSARIO.
